Calvin L. Hubbard Inventor

United States Patent Office.

CALVIN L. HUBBARD, OF NEW HAVEN, CONNECTICUT, ASSIGNOR TO "NEW HAVEN STEAM-HEATING COMPANY."

Design No. 3,075, dated June 30, 1868.

DESIGN FOR A SCREEN.

The Schedule referred to in these Letters Patent and making part of the same.

TO ALL WHOM IT MAY CONCERN:

Be it known that I, CALVIN L. HUBBARD, of New Haven, in the county of New Haven, and State of Connecticut, have invented a new Design for Screen; and I do hereby declare the following, when taken in connection with the accompanying drawing, to be a full, clear, and exact description of the same, and which said drawing constitutes part of this specification, and represents a front view of a portion of a screen.

This invention relates to a design for a screen, the object of which is an ornamental cover for steam-heaters, and the invention consists in the peculiar configuration of an open-work covering, consisting of one or more panels, according to the length of the screen.

Each panel is a lattice-work, interspersed with tracery, and supported by a column at each side, a bar across the top and bottom of the panel uniting the two columns and the tracery of the panel below the lower bar to the base, and above the upper bar, all as fully shown in the accompanying illustration.

What I claim, and desire to secure by Letters Patent, is—
The design, herein illustrated and described, for a screen.
